UNITED STATES PATENT OFFICE.

GOTTLOB HONOLD, OF STUTTGART, GERMANY, ASSIGNOR TO THE FIRM OF ROBERT BOSCH, OF STUTTGART, GERMANY.

ELECTRIC-CIRCUIT REGULATOR.

1,159,674.

Specification of Letters Patent.

Patented Nov. 9, 1915.

Application filed December 20, 1913. Serial No. 807,877.

To all whom it may concern:

Be it known that I, GOTTLÖB HONOLD, a subject of the Emperor of Germany, residing at Militärstrasse 4-8, Stuttgart, Germany, have invented certain new and useful Improvements in Electric-Circuit Regulators; and I do hereby declare the following to be a full, clear, and exact description of the invention, such as will enable others skilled in the art to which it appertains to make and use the same.

The present invention relates to electric regulators embodying a mass of finely divided resistance material, as grains of carbon, held in a container and subjected to the variable pressure of a pressure-member responsive to the magnetism of an electromagnet, wherein a strip of pliable insulating material, preferably taffeta silk, completes the closure for the resistance mass and forms a substantially frictionless guide for the pressure-member.

The container is made of electrically conducting material, and in order that the current shall pass through the resistance mass, the side wall of the container is insulated from the resistance mass while the strip of pliable material insulates the pressure-member from the container. Furthermore, the pliable strip, assisted if necessary by a plate spring or a spring structure, guides the pressure-member in movements of substantial parallel translation, so that the resistance mass is subjected to uniform pressure throughout, and so that a minimum movement of the pressure-member is required in order to produce the desired variation of resistance.

In the accompanying drawings, illustrating several modifications within my invention, Figure 1 represents a sectional elevation of a container for the resistance mass; Fig. 2 represents a sectional elevation of one form of my regulator; Fig. 3 represents a sectional elevation of a modified form of regulator; Fig. 4 represents a sectional elevation of a regulator showing a modified form of spring structure for assisting in guiding the pressure-member in movements of substantial parallel translation; Fig. 5 is a view similar to Fig. 4, but shows a different form of spring structure; and Fig. 6 is a section on line 6-6 of Fig. 5.

Referring to Fig. 1, the cylindrical container *c* of metal is provided with a circuit

terminal *j*, for connection to an electric circuit. The resistance mass *h*, consisting of finely divided material, such as grains of carbon, is in electrical contact with the bottom of the container, but is insulated from the side wall thereof by the sleeve *i* of insulating material such as glass. The pressure-member *a* of iron, resting on the top of the resistance mass, is responsive to the magnetic attraction of an electromagnet. 60 The outer edge of the pressure-member has a circumferential groove *k* in which is fastened a continuous strip *b* of pliable insulating material, preferably taffeta silk, which besides being pliable and insulating, 65 is durable. The strip *b* is laid over the upper edge of the sleeve *i* and a ring of insulating material *i'* of the width of the sleeve is clamped down on the strip by turning the rim of the container over the metal ring 70 *y*, to thereby securely fasten the outer edge of the strip *b* to the container. A ring *z* of felt or the like is fastened to the underside of the pressure-member in such manner that it slides against the side wall of the container and thereby keeps the particles of the resistance mass *h* from reaching the pliable strip *b*. In this way, the insulating properties and the durability of the fabric are 75 not impaired. Inasmuch as the strip *b* is 80 thin, it is held securely in place at its outer edge only by much pressure, and notwithstanding the fact that the contact surfaces may be machined accurately to fit, the strip may be damaged to such an extent as to 85 cause the pressure-member to lose its central position in the container. This difficulty is overcome in the construction shown in 90 Fig. 2 by clamping a downwardly extending part *b'* of the strip *b* between a brass 95 ring *n* and a ring *e* which is held in place by a comparatively slight pressure by the insulating sleeve *d* of glass. Owing to the extended surface of contact on the portion *b'* of the strip in the direction of movement 100 of the pressure-member, the edge of the part *b* of the strip need only be clamped loosely between the top *g* of the sleeve *d* and the rib *f* of the container. The edges of these parts are rounded off and thus there is little liability of damaging the material of the strip even if the contact surfaces do not fit so accurately. The inner edge of the strip *b* is 105 securely fastened in the circumferential groove *k* of the pressure member by pressing 110

a circular groove q in the lower flange p . The underside of the pressure member is, as in Fig. 1, provided with a felt ring z , and is also provided with a plate l of carbon 5 to insure more effective contact with the resistance mass. If desired, the ring n may be omitted and the downwardly extending portion b' of the strip pressed directly against the side wall of the container.

10 The electromagnet m is of the ordinary pot form, and its winding is connected to a circuit to be regulated in the well known way. The shaft o of metal, extending freely through the central bore r , is suspended by 15 an insulated connection from the plate spring s , which is fastened to an extension of the side wall of the container as shown. The spring s is arranged to oppose the attraction on the pressure-member a , which 20 forms the armature of the electromagnet, and furthermore by arranging this spring as far as possible from the strip b , the pressure-member is not only supported in central position in the container, but is guided 25 in movements of substantial parallel translation throughout the extent to which it is oscillated as a result of the magnetic attraction. In some cases, the amount of movement of the pressure-member a is of such 30 small magnitude that the strip b alone may serve to maintain the pressure-member in central position in the container and to guide the pressure-member in movements of substantial parallel translation. However, 35 the plate spring s renders this movement more nearly precise, especially if the spring is located as far as possible away from the strip b , and this action is obtained without materially increasing the substantially frictionless movement of the pressure armature. 40 In those cases in which the spring s is omitted, it is necessary to provide a spring or an equivalent device for opposing the attraction on the pressure-member.

45 The current to be regulated by the resistance mass h passes from the circuit terminal j' , through the bottom of the container c , and then with substantially uniform density through the resistance mass 50 into the pressure-member a , from which it leaves the regulator by way of the shaft o and circuit terminal j .

The construction embodied in Fig. 3 will now be understood from the foregoing. 55 However, the container c and the magnet m have a modified arrangement, while the plate spring s is supported on insulating material carried by the magnet and in contact with a cover t which is provided with 60 the circuit terminal j .

In the modification shown in Fig. 4, a 65 spring structure u, v is used for assisting the strip b in positioning and guiding the pressure-member a . The spring u consists of a tongue u_1 , formed from a disk, and ex-

tending to the center of the regulator. The spring u is, like the spring plate s of Figs. 2 and 3, secured at its edge. The free end of the tongue u_1 is held in a ring w , which is loosely mounted on a part x of reduced 70 section of the shaft. The closed yoke spring v is also pressed into the ring w , and it is provided with an adjustable tensioning device as shown. The guiding device assisting the strip b to position the 75 pressure armature a is, in this case, the leaf spring u_1 , which is tensioned on one side and whose arm has a length so chosen that the tilting, which results from the circular movement of its free end, practically disappears as a result of the slight movement of 80 the pressure armature. Instead of employing a spring tensioned on one side, a yoke spring u'' tensioned on both sides may be used as shown in Figs. 5 and 6, and in this 85 case there is a support for the armature shaft o and a spring action opposing the attraction on the pressure member, so that a substantially frictionless movement of the pressure member is obtained. By providing 90 a spring-supporting structure such as shown in Fig. 4, which in itself is capable of guiding the pressure-member in movements of substantially parallel translation, it is possible to arrange the spring structure closer 95 to the strip b without introducing an excessive amount of friction.

Reference is made to my copending application Serial No. 800,765 filed November 13, 1913, which is directed to various means 100 for preventing shifting of the resistance mass upon movements of the pressure member.

Having thus described my invention, what I claim is:

1. In a regulator for electric circuits, a mass of finely divided resistance material, a container for the resistance mass, an electromagnet having a magnetically-responsive pressure-member effective on the resistance mass to vary the resistance thereof, and a strip of pliable insulating material interposed between the periphery of the pressure-member and the side wall of the container to complete the closure for the resistance mass and to form a substantially frictionless guide for the pressure member; substantially as described.

2. In a regulator for electric circuits, a mass of finely divided resistance material, 120 a container for the resistance mass, an electromagnet having a magnetically-responsive pressure-member effective on the resistance mass to vary the resistance thereof, and a continuous strip of pliable insulating material having its inner edge held in a peripheral recess in the pressure-member and having its outer edge fastened in the side wall of the container so as to complete 125 the closure for the resistance mass and to 130

form a substantially frictionless guide for the pressure member; substantially as described.

3. In a regulator for electric circuits, a mass of finely divided resistance material, an electrically conducting container for the mass, a sleeve of insulating material extending along the inside surface of the container from the base thereof to substantially the level of top of the resistance mass, an electromagnet having a magnetically-responsive pressure-member effective on the resistance mass to vary the resistance thereof, and a strip of pliable insulating material fastened to the pressure-member and held between the insulating ring and the side wall of the container so as to complete the closure for the resistance mass and to form a substantially frictionless guide for the pressure member; substantially as described.

4. In a regulator for electric circuits, a mass of finely divided resistance material, a container for the resistance mass, an electromagnet having a magnetically-responsive pressure-member effective on the resistance mass to vary the resistance thereof, and a strip of woven fabric of insulating material fastened to the pressure-member and to the container so as to complete the closure for the resistance mass and to form a substantially frictionless guide for the pressure-member; substantially as described.

5. In a regulator for electric circuits, a mass of finely divided resistance material, a container for the resistance mass, an electromagnet having a magnetically-responsive pressure-member effective on the resistance mass to vary the resistance thereof, and a continuous strip of taffeta silk having its inner edge clamped in a peripheral groove in the pressure-member and having its outer edge fastened to the container so as to complete the closure for the resistance mass and to form a substantially frictionless guide for the pressure-member; substantially as described.

6. In a regulator for electric circuits, a mass of finely divided resistance material, a container for the resistance mass, an electromagnet having a magnetically-responsive pressure-member effective on the resistance mass to vary the resistance thereof, and a strip of pliable insulating material interposed between the periphery of the pressure-member and the side wall of the container to complete the closure for the resistance mass and to form a substantially frictionless guide for the pressure-member, said pressure-member carrying around its edge a strip of material extending to the side wall of the container to keep the resist-

ance material from the pliable strip; substantially as described.

7. In a regulator for electric circuits, a mass of finely divided resistance material, a container for the resistance mass, an electromagnet having a magnetically-responsive pressure-member effective on the resistance mass to vary the resistance thereof, and a strip of pliable insulating material interposed between the periphery of the pressure-member and the side wall of the container to complete the closure for the resistance mass and to form a substantially frictionless guide for the pressure-member, said pressure-member carrying a carbon plate in contact with the resistance mass and also carrying around its edge a strip extending to the side wall of the container to keep the resistance material from the pliable strip; substantially as described.

8. In a regulator for electric circuits, a mass of finely divided resistance material, a container for the resistance mass, an electromagnet having a magnetically-responsive pressure-member effective on the resistance mass to vary the resistance thereof, a strip of pliable insulating material interposed between the periphery of the pressure-member and the side wall of the container to complete the closure for the resistance mass, and a resilient plate separated from the pliable strip and effective therewith to guide the pressure-member in movements of substantial parallel translation; substantially as described.

9. In a regulator for electric circuits, a mass of finely divided resistance material, an electrically conducting container for the mass, a sleeve of insulating material extending along the inside surface of the container from the base thereof to substantially the level of the top of the resistance, an electromagnet having a magnetically responsive pressure-member effective on the resistance mass to vary the resistance thereof, a strip of pliable insulating material having its inner edge fastened in a peripheral groove in the pressure-member and having its outer edge held between the insulating ring and the side wall of the container so as to complete the closure for the resistance mass, and a plate spring separated from the pliable strip and effective therewith to guide the pressure-member in movements of substantial parallel translation; substantially as described.

In testimony whereof I affix my signature, in presence of two witnesses.

GOTTLOB HONOLD.
